UNITED STATES PATENT OFFICE.

LOYAL C. TABER, OF DANFORTH, NEW YORK.

TRACTION-ENGINE.

SPECIFICATION forming part of Letters Patent No. 329,238, dated October 27, 1885

Application filed August 20, 1885. Serial No. 174,852. (No model.)

To all whom it may concern:

Be it known that I, LOYAL C. TABER, of Danforth, in the county of Onondaga, in the State of New York, have invented new and useful Improvements in Traction-Engines, of which the following, taken in connection with the accompanying drawings, is a full, clear, and exact description.

This invention relates to the class of traction-engines which have the propelling-power transmitted to the forward wheels as well as to the hind wheels, and has particular reference to the engine for which I have obtained Letters Patent No. 294,930, dated March 11, 1884.

In the manufacture and use of said engine I have found certain defects, which by my present invention are effectually remedied, as will be hereinafter explained.

In the accompanying drawings, Figure I is an elevation of my improved traction-engine, taken at the side which carries the train of gears by which power is transmitted to the four carrying-wheels, the engine proper and its connection with the driving-shaft being omitted, as such are immaterial to the illustration and description of the invention. Fig. II is an elevation of the opposite side of that part of the traction-engine to which my improvements are applied, said figure being partly a sectional view taken on line $x-x$ in Fig. III; and Fig. III is a front end view.

Similar letters of reference indicate corresponding parts.

A represents the boiler, which is formed at its rear end with the downwardly-extended water-jacketed fire-box A'. Said boiler is supported on the axles a a' at opposite ends, and nearly the entire weight of the boiler, engine, and of the greater portion of the gears falls onto the central portion of the boiler, the rigidity of which has heretofore been depended upon for resisting the weight and transmitting it to the axles. Experience has proved that the aforesaid weight produces such a strain on the seams of the boiler, especially at the junction of the forward portion of the fire-box with the boiler, as to weaken or open the seam thereat. To obviate this defect I extend from the bottom of the fire-box A' to the upper part of the post K, by which the forward end of the boiler is supported on the

axle, a brace, B, which is secured at its rear end to a knee, f, embracing the bottom corner of the forward portion of the fire-box, and firmly bolted thereon, said knee being provided with forward-projecting ears n n' between two of which the end of the brace enters, and is secured thereto by a bolt, o, passing through said ears and end of the brace. The forward end of the brace is inserted between lugs or ears p , formed on the rear of the bearing-post K, to which lugs or ears the brace is connected by a bolt, o', passing through said parts. The bolts o o' can be withdrawn and the brace removed when required for repairs or renewal.

The traction-wheels W W receive propelling-power from the driving-shaft C by means of a train of gears, F F F F, and a spur-wheel, E, mounted on gudgeons which are secured to the side of the boiler, as represented in Fig. I of the drawings. Said spur-wheel E meshes in a pinion, D', fastened on the driving-shaft, and engages also a gear-wheel, O, which in conjunction with other gears, hereinafter described, transmits motion to the forward axle, a. On this axle I fit loosely a sleeve, s, which is provided on top with a socket or concave step, b, of the form of a section of a sphere, and in this socket is seated the bearing-post K, which is firmly bolted to the under side of the boiler, and has its lower end of semi-spherical shape, corresponding to the socket b, in which it is stepped. The boiler is thus mounted on the forward axle by a ball-and-socket joint, which allows the said axle to oscillate in all directions.

In order to confine the bearing-post K in the socket b without interfering with the aforesaid universal movement of the axle, I provide the under side of the axle with a downward-projecting stud-pin, u, to which I connect the forward end of the reach r, which extends across the under side of the sleeve, and has an eye for the reception of said stud-pin. Said end of the reach projects forward from the sleeve s, and is provided with another eye for the reception of the lower end of a coupling bolt or link, d, which has its upper end pivoted on the front of the post K, at a point in a line extending horizontally through the center of the sphere formed on said post. The lower end of the link d passes through the end of the reach r, and is provided on the under side

thereof with nuts, which hold the reach up against the sleeve *s* and complete the coupling of the ball-and-socket joint between the boiler and axle. The pivotal connection of the link on the post *K* allows the axle to freely oscillate in a vertical plane, as indicated by dotted lines in Fig. III of the drawings. The rear end of the reach is inserted between the two ears *n n* of the knee *f*, and is connected therewith by the bolt *o*, passing through it, said knee consisting of a single plain casting, which has a firm bearing on the shell of the water-jacket surrounding the fire-box, and serves as a convenient and secure fastening for the brace *B* and reach *r*. Said brace and reach thus have in common one attachment at their rear ends, and this is a very important feature of my invention, inasmuch as the reach has to resist the tendency of the forward axle being crowded rearward by the encounter of its traction-wheels with obstructions on the road, and also the tendency of the axle being crowded forward by the strain transmitted to the axle by the engagement of the pinion *P* with the gear *R*, and these strains are transmitted by the reach to the knee *f*, where they are resisted by the brace *B*, which latter transmits the strain to the rigid post *K* on the forward end of the boiler, and thus completely relieves the rear portion of the boiler of said strain. The post *K* is hollow, and has on one side an opening, *c*, and on the opposite side a rigid horizontal sleeve, *h*, projecting therefrom. Diametrically through the semi-spherical portion of the post *K* is extended a counter-shaft, *L*, one end of which is journaled in the sleeve *h*, and the opposite end projects through the opening *c*, and is journaled in a box, *e*, attached to a vertical rib rising from the sleeve *s*. This counter-shaft is provided with a universal joint, *M*, in the center of the semi-spherical part of the post *K*, which joint allows one end of the counter-shaft to follow the axle *a* in its oscillatory movements, while the opposite end of said shaft is maintained parallel with the driving-shaft *C* by means of the sleeve *h*. This linearly-confined end of the counter-shaft has attached to it a pinion, *N*, which meshes in a pinion, *N'*, mounted on a gudgeon rigidly attached to the boiler, and on the side of the pinion *N'* is the gear-wheel *O*, which receives motion from the driving-shaft *C*, as hereinbefore described.

55. On the vibratory end of the counter-shaft *L* is a pinion, *P*, which meshes in a compensating gear, *R*, mounted on the axle *a*, said compensating gear being adapted to transmit motion to the axle at varying speed when turning the axle to guide the engine around curves of the road.

The engine is guided by means of the usual steering-chains, *h h*, which are connected to the ends of the sleeve *s*, and are wound in opposite directions on a shaft, *t*, which is under the control of the operator, by a hand-wheel on the end of a shaft carrying a worm

which engages a worm-gear on the end of the shaft *t*, in the usual and well-known manner, not necessary to be herein illustrated.

In the operation of this engine it has been found that it is necessary to limit the turning of the axle *a*, so as to guard against cramping of the gears *P R* and the binding of the flexible part of the counter-shaft *L* against the sides of the opening *c* in the bearing-post *K*; and to obviate such injurious effects I employ check-chains *l*, which are at one end hung loosely on the shaft *t*, so as to prevent their being wound on the shaft, and thus have their rear attachment stationary and independent of the steering-chains. The opposite ends of the check-chains are securely coupled to the steering-chains at any suitable point between the shaft *t* and the axle-sleeve *s*. Said check-chains are of such length that in the operation of turning the axle laterally the check-chain which is coupled to the unwinding or paying-out steering-chain is drawn taut and caused to arrest the movement of said steering-chain.

Having described my invention, what I claim as new, and desire to secure by Letters Patent, is—

1. In combination with the boiler *A A'* and forward axle, *a*, the reach *r*, extending from the axle to the rear portion of the boiler, and the brace *B*, extending from the forward portion of the boiler to the rear portion of the same, and having its attachment at the rear end, in common with that of the reach, substantially as set forth.

2. In combination with the boiler *A*, semi-spherical bearing-post *K*, and forward axle, *a*, the sleeve *s*, provided on top with the socket *b* and on the bottom with the stud-pin *u*, the reach *r*, extending across the under side of the sleeve, and provided with an eye for the reception of the stud-pin, and the coupling-link *d*, pivoted on the post *K*, and connected with the forward end of the reach, whereby said post is retained in the socket without interfering with the oscillations of the axle, substantially as set forth and shown.

3. In combination with the boiler *A*, having the downwardly-extended fire-box *A'*, and reach *r* and brace *B*, the knee *f*, embracing the bottom corner of the forward portion of the fire-box, and having forward-projecting ears *n n n'*, and bolt *o*, for the attachment of the reach and brace, substantially as described and shown.

4. In combination with the boiler *A*, axle *a*, sleeve *s*, provided with the socket *b*, hollow semi-spherical bearing-post *K*, provided with the side opening, *c*, compensating gear *R* on the axle, and the counter-shaft supported on the sleeve and having a universal joint in the hollow post *K*, and provided with the pinion *P*, meshing in the gear *R*, and the steering-chains *h*, wound in opposite directions on the shaft *t*, and connected to the ends of the sleeve *s*, as described, the check-chains *l*, having their rear ends attached stationary

and independent of the steering-chains, and their forward end securely coupled to the steering-chains, and each check-chain of a length to be drawn taut by the unwinding of the steering-chain, to which it is connected, whereby the action of the steering-chains is limited, to prevent the binding of the counter-shaft in the side opening of the bearing-post, and injury to the same and to the gears P R, substantially as set forth.

In testimony whereof I have hereunto signed my name and affixed my seal, in the presence of two attesting witnesses, at Eaton, in the county of Madison, in the State of New York, this 14th day of August, 1885.
